HANDLE RETAINING FIXTURE

Roy R. Hart, San Jose, Calif.

Application May 20, 1941, Serial No. 394,303

2 Claims. (Cl. 24—249)

This invention relates in general to improvements in handle retaining fixtures of the type commonly known as broom holders, such as are adapted to engage the handles of household brooms, mops, etc., suspended from the device, which is secured to a wall or other vertical surface some distance above the floor level; this invention in particular comprising improvements over the device shown in my United States Letters Patent No. 1,864,817 dated June 28, 1932.

The present invention employs broadly the same principle as the device shown in my identified patent; namely, the weight of the broom causes a swinging holding member to bind or grip the handle and prevent downward slipping movement thereof.

In handle retaining fixtures which employ a metallic member to engage the broom handle, the frictional engagement of such member with the handle sometimes is not sufficient to positively hold the handle against slipping, particularly where the holding member is of a type adapted to engage handles of different diameters. Further, the metallic member tends to mar and indent the surface of the handle, and the latter becomes rough and unsightly.

The principal objects of the present invention are to provide a handle retaining fixture which is operative to positively grip handles of different diameters; and to construct the fixture in such manner that the handle is engaged only by resilient gripping material, and without metal contact.

Another object of the invention is to provide a handle retaining fixture including a swinging member having a handle receiving aperture open to one side thereof; said member including jaws on opposite sides of such aperture, the outermost jaw being parallel to the axis of such swinging member and to the wall to which the fixture is attached. Such parallelism of the outer jaw assures against lateral displacement of the handle from the aperture of the swinging member.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a plan view of the device gripping a handle of relatively large diameter.

Figure 2 is a plan view of the device gripping a handle of relatively small diameter.

Figure 3 is a side elevation of the device in use.

Figure 4 is a cross elevation on line 4—4 of Fig. 2.

Referring now more particularly to the characters of reference on the drawing, the device comprises a wall bracket including a back plate 1 secured to a wall 2 by suitable means such as screws 3; such plate extending horizontally and at its ends being formed with forwardly projecting, parallel ears 4. The ears 4 are formed with horizontally aligned openings 5.

The swinging holding member comprises a plate 6 having a rearward projection 7 which engages between ears 4 with an easy fit, and opposed lugs 8 extend from the sides of projection 7 through openings 5, forming the axis about which the plate 6 may swing. Some distance below the horizontal plane of openings 5 the ears 4 are formed with stop-shoulders 9, against which the swinging plate 6 is adapted to engage, whereby to limit downward movement of said plate.

The plate 6 is of substantial size, and is formed with an aperture 10, which opens to one side of such plate; the portions of the plate along opposite sides of such aperture forming what may be termed jaws which are indicated at 11 and 12 respectively.

The inner or working edge of jaw 11 is disposed parallel to wall 2 and the axis of the plate, as is indicated by broken line 13. The working edge of the other jaw 12 diverges from the jaw 11 in a direction from the closed to the open end 35 of aperture 10, and at an acute angle to the axis of the swinging plate 6, whereby said aperture 10 decreases in width from its open end to its closed end.

The swinging plate 6, about the edge which borders aperture 10, is formed with a channel 14, which opens into the aperture; such channel being of dovetail configuration except at the closed end of aperture 10, where the channel is straight sided, as shown in Fig. 4. A strip 15 of resilient and compressible friction gripping material, such as rubber, is seated in and extends from end to end of channel 14; such strip being of sufficient size to project inwardly a short distance beyond the inner edges of the channel, and as is clearly shown in Fig. 2. The exposed or handle contacting face of strip 15 may be roughened in a suitable manner, as by knurling. It should be noted that such faces of the strip 15 are parallel to the corresponding jaws.

The curvature of the plate at the inner end of

the aperture and likewise the curvature of the strip 15 at such point are not on a true circle, but are flattened somewhat, as at 16.

In use, the plate 6 is held horizontally and the handle H to be retained is disposed vertically and moved laterally into the aperture 10 until the gripping strip 15 of jaws 11 and 12 firmly engage the broom handle. Thereupon, the plate and handle are released, and the weight of the handle tends to swing the plate downwardly, immediately effecting a positive grip or binding action between strip 15 of both jaws and such handle; the handle becoming slightly embedded on opposite sides in the portions of the gripping strip corresponding to the jaws. By virtue of the fact that jaw 11 and its gripping strip portion are parallel to the wall 2 and the axis of the plate 6, there is no tendency for the handle to shift laterally and in the direction of the open end of aperture 10. In addition, it is not possible for 20 the handle to be marred or scratched.

When a handle H' of the smallest diameter within the limit of capacity of the device is engaged in aperture 10, it abuts against the bottom of the latter, but does not make full contact due 25 to the non-concentricity or flattening, as at 16, of the end of such aperture and the corresponding portion of the binding strip. By reason of this non-concentricity, the handle, when gripped by the device, is not urged in the direction of the 30 open end of the aperture when the gripping action takes place, as would tend to take place if the inner end of the aperture were concentric with the handle.

It is to be noted that the strip 15 is initially of the same cross sectional form as the channel, the sides of the latter being crimped in after the strip is disposed in place. In this manner, the strip cannot escape, yet is not compressed and thus does not have a curved and undesirable bulge 35 on its gripping face which would be formed if the rubber was compressed by the channel.

From the foregoing description, it will be readily seen that I have produced such a device

as substantially fulfills the objects of the invention as set forth herein.

While this specification sets forth in detail the present and preferred construction of the device, 5 still in practice such deviations from such detail may be resorted to as do not form a departure from the spirit of the invention, as defined by the appended claims.

Having thus described my invention, what I 10 claim as new and useful and desire to secure by Letters Patent is:

1. In a handle retaining fixture which includes a bracket adapted to be secured on a wall, and a plate hinged to the bracket for vertical swinging movement and having a handle receiving aperture cut therein lengthwise of the hinge axis and open to one side of the plate; the portions 15 of the plate on opposite sides of said aperture forming handle engaging jaws, the working edge of the jaw farthest from the axis of the plate being parallel to said axis and to the wall, and the working edge of the jaw nearest said axis diverging relative to said first named jaw from the closed to the open end of said aperture.

2. In a handle retaining fixture which includes a bracket adapted to be secured on a wall, and a plate hinged to the bracket for vertical swinging movement and having a handle receiving aperture cut therein lengthwise of the hinge axis and open to one side of the plate; said plate 30 having a continuous, inwardly opening channel bordering said aperture, and a one-piece friction gripping strip fitted in said continuous channel from end to end thereof and extending into the aperture beyond the adjacent edges of said channel, the extending portions of said strip along opposite sides of said aperture forming handle engaging jaws, and the channel being deformed to dove-tail configuration in cross section and 35 into frictional engagement with the strip along the portions of said strip forming the jaws whereby to secure the strip in said channel.

ROY R. HART.
